UNITED STATES PATENT OFFICE

WILLIAM P. LEAR, OF CHICAGO, ILLINOIS, ASSIGNOR TO GALVIN MANUFACTURING CORPORATION, OF CHICAGO, ILLINOIS, A CORPORATION OF ILLINOIS

DESIGN FOR A RADIO CONTROL DEVICE

Application filed July 14, 1930. Serial No. 36,343. Term of patent 14 years.

To all whom it may concern:

Be it known that I, WILLIAM P. LEAR, a citizen of the United States, residing at Chicago, in the county of Cook and State of Illinois, have invented a new, original, and ornamental Design for a Radio Control Device, of which the following is a specification, reference being had to the accompanying drawing, forming part thereof.

The figure is a perspective view showing two sides and the top of the control device

embodying the features of the novel design, the side opposite side *a* being identical to side *a*.

I claim:

The ornamental design for a radio control device substantially as shown and described.

In witness whereof, I hereunto subscribe my name this 3rd day of July, 1930.

WILLIAM P. LEAR.
